UNITED STATES PATENT OFFICE.

PAUL RATHMANN, OF BODENBACH, CZECHOSLOVAKIA, ASSIGNOR TO ELEKTROTECHNISCHE FABRIK SCHMIDT & CO., GESELLSCHAFT M. B. H., OF BODENBACH, CZECHOSLOVAKIA.

PORTABLE ELECTRIC LAMP.

Application filed December 29, 1927, Serial No. 243,321, and in Czechoslovakia April 21, 1927.

My invention relates to portable electric lamps such as flash lights, hand lamps and the like. It is an object of my invention to provide more reliable means for facilitating 5 the insertion of the battery in such lamps.

The portable lamps hitherto in use involve the drawback that the insertion of the battery requires great care as the battery must be inserted in a definite position 10 so that its contact springs will engage the two contacts of the casing. It is not easy to insert the battery properly in the dark to make the lamp operate immediately. Another weak point of the lamps hitherto used 15 is the switch which often fails and renders the lamp inoperable.

Both these drawbacks are overcome according to this invention by duplicating one 20 of the two contacts in the casing, so that the battery may be inserted in any position with respect to the duplicate contact, and by providing a switching lever which is electrically 25 connected with the casing and with one pole of the lamp and cooperates with a contact spring forming the other pole of the lamp 30 and insulated from the casing. The contact spring locks the switching lever in two positions but makes contact with it only in one position, insulating means being provided 35 for breaking the electrical connection in the other position. Preferably such insulating means are secured to the switching lever.

My invention simplifies the design of casings for lamps of the kind described to such 35 an extent that they can be manufactured at very low cost and on a quantity production basis.

In the drawings affixed to this specification 40 and forming part thereof, a flash light equipped with my improvements is illustrated diagrammatically by way of example.

In the drawings

Fig. 1 is a rear end elevation of the lamp 45 partly broken open,

Fig. 2 is a central vertical section of the lamp,

Fig. 3 is a part sectional elevation showing 50 the switching lever and its accessories on a larger scale.

Referring now to the drawings, and first to Figs. 1 and 2, 1 is the duplicate contact piece or bridge, being a flat body of sheet

metal or the like, with two flanges 2 each 55 constituting a contact for the contact spring of the battery. The flanges 2, 2 are attached to the side walls 3 of the casing but insulated from them by insulating strips 4 and 7. Tongues or other means 5 are provided at 60 the contact piece for securing it in the casing, such tongues being inserted in slots of the inner insulating strip 4, bent over so as to hub the strip, and held out of contact with the walls 3 by the outer strip 7.

6 is a threaded socket for inserting an incandescent lamp, not shown, so that the lamp will make contact with the body of the bridge 1 intermediate its flanges 2, 2.

It will be understood that when a battery, 70 not shown, is inserted between the flanges 2, 2 of the part 1 it does not matter in which position it is with respect to the flanges, as its contact spring will engage one of the flanges 2, 2 in any position. The other contact spring of the battery will be engaged by the 75 spring 9.

Referring now to Fig. 3, 8 is a switching lever which is pivoted in the casing at 10 and electrically connected with the second pole of the incandescent lamp, 9 is a contact 80 spring secured to, but insulated from the casing by the insulating strips 4, 7, and 11 is a strip of insulating material at one side of the V-shaped base of the switching lever 8. The other side is not insulated.

In operation and in the position illustrated 85 in Fig. 3, the plain side of the V-shaped end of lever 8 makes contact with the spring 9 and is held in position by the reaction of the spring, contact being now established between 90 the lamp and the battery. By throwing over the lever into its opposite position, as shown in Fig. 2, the insulating strip 11 on the other side of the V is brought into engagement with the spring 9 so that the lamp circuit is broken. 95

Instead of securing the insulating strip 11 at the switching lever it might be provided at the spring 9 so as to be engaged by the lever 8 only in one of its positions.

I wish it to be understood that I do not desire to be limited except by the scope of the claim to the exact details of construction shown and described for obvious modifications will occur to a person skilled in the art.

I claim:—

A portable electric lamp comprising a cas-

ing, a contact bridge having a flange secured to and insulated from each side wall of said casing and adapted to be engaged by a contact of a battery in said casing, a lamp socket in said casing facing said bridge intermediate its flanges, a contact spring, a switching lever adapted to cooperate with said contact spring

and to be held in two positions by the reaction of said spring, and an insulating strip adapted to be interposed between said contact and said spring in one of the positions of said lever.

In testimony whereof I affix my signature.

PAUL RATHMANN.
